Int. Cl. D26—04

U.S. Cl. D26—8

FIG. 2

FIG. 1

FIG. 4

FIG. 3

FIG. 5

FIG. 1 is a perspective view of a bulb for an electric lamp showing our new design;

FIG. 2 is a perspective view of a second embodiment of our new design;

FIG. 3 is a perspective view of a third embodiment of our new design;

FIG. 4 is a perspective view of a fourth embodiment of our new design; and

FIG. 5 is a side elevational view of the bulb shape of the embodiment of FIG. 1, it being understood that all of the embodiments of bulb shapes are identical in side profile with the exception of the surface ornamentation.

The base for the bulb is shown in broken lines for illustrative purposes only.

The bulb is shaded in FIGS. 1 and 5 to show contour; in FIG. 2 to primarily show surface ornamentation; and in FIGS. 3 and 4 to show contour and contrast.

We claim:

The ornamental design for a bulb for an electric lamp, substantially as shown and described.
